UNITED STATES PATENT OFFICE.

WILLIAM TODD, OF KALAMAZOO, MICHIGAN.

DESIGN FOR A PAPER FILE OR HOLDER.

SPECIFICATION forming part of Design No. 29,918, dated January 3, 1899.

Application filed May 6, 1897. Serial No. 635,428. Term of patent 3½ years.

To all whom it may concern:

Be it known that I, WILLIAM TODD, a citizen of the United States, residing at the city of Kalamazoo, in the county of Kalamazoo 5 and State of Michigan, have invented a certain new and useful Design for a Paper File or Holder, of which the following is a specification.

My invention relates to a design for a paper file or holder, illustrated in the accompanying drawing, forming a part of this specification, where a single perspective view of the file is shown.

As shown in the drawing, the leading or material feature of my design is a spring clasp or holder B. The file is made of wire, which

extends down where it is formed into a spiral B', then extends upwardly and outwardly at C'. It will be noted that the clasps are very artistic in their appearance.

Having thus described my invention, what I claim as new, and desire to secure by Letters Patent, is—

The design for a spring paper file or holder substantially as described and shown.

In witness whereof I have hereunto set my hand and seal in the presence of two witnesses.

WILLIAM TODD. [L. S.]
